UNITED STATES PATENT OFFICE.

FOSTER J. HULL, OF HAGERSTOWN, MARYLAND, ASSIGNOR TO PANGBORN CORPORATION, OF HAGERSTOWN, MARYLAND, A CORPORATION OF MARYLAND.

SAND-BLAST DEVICE FOR CONTROLLING THE DIRECTION OF THE ABRASIVE STREAM.

Application filed January 5, 1926. Serial No. 79,300.

The invention relates to an abrading machine of the type known to the trade as sand blast machines, though in these machines any variety of comminuted abrasive material may 5 be used and steel abrasives are preferred.

The machine has a rotary container or barrel in which the castings or other articles being treated are agitated by the rotation of the barrel to expose their various surfaces in 10 turn. The abrasive carried by a jet of air under pressure, the machine being for this reason referred to as of the direct pressure type, is injected into the barrel at the centres of the axial ends by means of a nozzle or nozzles, there being preferably one at each end, 15 the manner of mounting the nozzle and the nozzle construction or more particularly the method and device for controlling the adjustable directioning of the abrasive stream 20 being the subject of the invention.

Different loads for different types of work take different positions in the barrel, and the work climbs higher or lies at a lower level in the barrels, depending upon the contour of 25 the surfaces, the thickness, weight and general construction of the members or pieces composing the material being treated. It is understood by those familiar with the art that in the rotation of the barrel the load climbs on the upwardly rotating side of the barrel and is therefore inclined downwardly in the direction of rotation, i. e., when the barrel is rotating clockwise, the load is inclined downwardly to the right, and to get 30 the best results, the centre of the blast is directed at or near the centre of the exposed surface of the load. It is therefore desirable that the machine be capable of adjustment as to the direction of the blast.

An object of the invention is to so construct 40 the machine as to handle all kinds of work and with the barrel variously filled, to the best advantage without extensive or difficult changes of the apparatus. The present device makes it possible to make all adjustments as to the position of the nozzle and direction of the blast without disassembling the apparatus in any way or having access to the inside of the drum.

The sand or other abrasive is deflected by 50 the load and may be said to splash from the castings, and one of the objects of the invention is to produce a nozzle mounting which gives at all times a tight closure of the casing

or a seal around the nozzle preventing escape 55 of the abrasive and dust from the casing.

Wear on the different parts of the nozzle which direct and are therefore exposed to the abrasive is excessive, and there is also a tendency to clog, making frequent dismantling 60 of the nozzles either for replacement or to remove obstructions necessary, and the structure of the present invention, i. e., the nozzle and support and adjusting means are so devised that the nozzle can be taken from the 65 case instantaneously and likewise taken down, inspected, and the various parts replaced without delay.

One of the important results obtained is the 70 easy and quick adjustment of the nozzle in all directions by means of a universal carrier for the nozzle, and a movable support by which the location of the nozzle is adjusted, so that by thus changing the position of the nozzle support, the nozzle may be turned 75 through a wide angle in any direction relatively to the axis of the barrel and still enter the opening in the barrel which is preferably but a little larger than the nozzle. Further, 80 the various adjustments of the nozzle are made without special tools, with an ordinary wrench. The nozzle tip which is the member most frequently replaced, can be removed and installed without delay, and the nozzle is held in position by a simple type of lever lock 85 which is instantaneous in its operation in engaging and releasing the nozzle.

In the accompanying drawing I have illustrated a device for controlling the adjustable directioning of the abrasive material and the 90 various details thereof in the preferred form.

In the drawing—

Figure 1 is a fragmentary central vertical section on the axis of the barrel viewing the nozzle and mounting in detail.

Figure 2 is a section at right angles to the plane of Figure 1 and taken on the line 2—2 Figure 1.

Figure 3 is a front elevation of the sand blast apparatus, the casing being broken 100 away and the barrel being shown in section.

Referring to the drawings by numerals, each of which is used to indicate the same or similar parts in the different figures, the apparatus as shown comprises a casing 1 more 105 fully illustrated in my co-pending application No. 13,587, a rotary barrel 2 having an opening 3 for the nozzle in the axial end wall

preferably at the centre or axis, and a nozzle 4 directed into the opening 3, with adjustable means for supporting the nozzle and controlling the direction of the abrasive stream.

5 The nozzle carrier comprises first a spherical member or ball 7 in which the nozzle member 4 is mounted. This ball has opposite openings 8 and 9 which may be referred to as at the opposite ends of a long diameter and 10 in a general way as for the purpose of admitting the nozzle at one end and for the exit of the sand blast at the other.

As shown the opening 8 is at the bottom or end of a protruding chamber or socket 10 formed by or in the walls of the sphere or ball 7, and the nozzle tip 12 protrudes from said opening 8 and projects into the barrel opening 3, which is preferably but little larger than the nozzle tip. The other or rear end 20 of the nozzle, as shown, has a circumferential shoulder 14 which fits in the opening 9 in the sphere or ball. The nozzle is inserted tip first, and is held in the sphere by a lock 15 engaging the shoulder 14. The nozzle may 25 be secured in any preferred way, the lock being shown in the form of a lever loosely pivoted on the ball as by a pin or bolt 16, and normally hanging by gravity in centre position. The upper or locking end of the 30 lever 17 is of a length slightly greater than its width and in centre position as shown it projects over the shoulder or flange 14 of the nozzle, holding the latter in position in the sphere, but by swinging the lever 15 in either 35 direction to a position at a sufficient angle with the position shown, the end 17 is swung clear of the shoulder 14. It is therefore apparent that by merely displacing the lever 15 by a touch of the finger of the hand gripping 40 the hose 18, the nozzle is released and may be instantly removed from the ball.

The spherical member or ball carrier 7 is mounted for universal adjustment in the plate 1 which is a part of the outer housing or casing 45 of the apparatus. The mounting consists of a plurality of cupped rings, namely supporting ring 21 and clamping ring 22, each presenting to the sphere or ball an inner surface 23 and 24, respectively, preferably in 50 the form of a spherical section or zone, of a little less inside diameter than the greatest diameter of the ball, said surfaces being oppositely inclined toward the centre of the sphere or ball. These rings are placed on opposite sides of the equator of the sphere or ball, or otherwise stated, the ball being placed 55 between the rings, the latter are drawn together and into contact with the opposite slopes of the spherical outer surface of the ball by means of bolts 25 seated in and passed through the respective rings and tightened by nuts 26. The bolts are spaced about the periphery of the rings by any suitable arcs and placed parallel to the axis of the rings.

60 65 The nozzle is universally adjustable for di-

rection about the centre of the ball 7, the adjustment being accomplished by slightly loosening the nuts 26, moving the nozzle and ball to the desired position and then taking up on the bolts 25 by means of the nuts 26, 70 drawing the rings 21 and 22 toward each other and applying sufficient pressure thereby to the surface of the ball to hold it in adjusted position.

On account of the necessarily restricted 75 proportions of the hole 3 at the centre of the axial end of the barrel, it is also necessary or desirable in order to effect accurate directioning of the abrasive stream of sufficient scope to make it possible to treat all loads to the best advantage to change the location of the ball and nozzle within a limited scope, and to accomplish this change and secure the parts in their adjusted position quickly and easily, and at the same time to maintain a tight closure of the casing. To this end the supporting ball ring 21, is formed or mounted on a movable plate which closes the opening in the casing. This is shown in the form of a circular support or supporting plate 28, which 80 circular support or plate is in turn mounted for rotary adjustment in a circular opening 29 in the casing, the ball being eccentrically mounted in the plate, and the centre of the plate or support being preferably somewhat 85 higher than the centre of the barrel, so that the abrasive stream is normally directed downwardly against the surface of the load which usually fills the barrel slightly less than half full.

100 The plate or support 28 as shown co-operates with a clamping ring 30 on the outside of the casing, the clamping ring 30 and the support 28 being of similar outside diameter and the support being inside of the casing, the edges of which surrounding the opening 29 are clamped between the support or plate 28 and the ring 30, the ring and support being drawn together by bolts 31 and nuts 32 placed at suitable intervals about the circumference of the ring. The location of the nozzle is changed in adjusting the direction of the stream of abrasive by unclamping the plate 30 rotating it until the nozzle is located as cleared and reclamping it.

110 The nozzle being easily removed from the ball 7 is likewise easily dismantled for replacing the tip and for freezing the nozzle or clearing it in case it becomes plugged by accumulation of the abrasive. The manner 120 of locking the nozzle in the ball and releasing it has already been described. The tip 12 is held in the nozzle by a screw cap 35 having an opening 37 for the tip. The cap engages a shoulder 38 on the tip, which when the cap 125 is screwed up presses against a soft washer 39 bearing on the end of the main portion 4 of the nozzle. The reduced inner end of the tip at 40 projects and fits inside the main body 4 of the nozzle. The outer end 41 of the tip 130

projects through the opening 8 in the protruding chamber 10 of the ball 7, to and into the opening 3 at the centre of the axial end of the barrel, which opening is as shown preferably bevelled as at 42 to provide for free movement of the nozzle to its various positions of adjustment in directioning the abrasive stream as already outlined.

It will be understood that the adjustment 10 of the position of the nozzle by rotation of the support or supporting plate 28 moves the ball 7 and the portion of the nozzle therein on a substantially circular path, the radius of which is the eccentricity of the position of the ball 15 as to the plate 28, and if the ball 7 and the plate 28 be unclamped and moved at the same time, the hose 18 being considered as completely flexible, the end of the nozzle being confined in the opening 3 in the barrel, 20 the axis of the nozzle may be caused to generate a conical surface or a surface which is substantially conical, the projecting end 41 of the nozzle being substantially the apex of the cone. It is of particular importance 25 that by adjusting the position of the plate 28 rotatively, the position of the ball 7 and the portion of the nozzle therein may be so changed that by means of this adjustment and the universal adjustment of the ball, the 30 abrasive stream may be applied to any portion of the surface of the load which it is desired to treat, and this is accomplished without the necessity for having the end of the nozzle project within the barrel where it 35 would be exposed to the action of the abrasive, nor is it necessary to have the barrel opening much larger than the diameter of the end of the nozzle.

An object of the invention most effectually 40 accomplished by this device is the complete sealing of the casing around the nozzle, preventing the escape of dust, which is an important element in the cleaning of castings and the like. While the nozzle is universally 45 and freely and quickly adjustable, there are no apertures around the nozzle for the escape of dust or abrasive from the casing.

The operation of the device is believed to be clear from the preamble and description. 50 The operator having observed the position of the load 45, if he finds the nozzle is not so placed as to direct the abrasive stream downward against the surface of the load, loosens the nuts 26 and 32, and by turning the circular eccentric support 28, and at the same 55 time rocking the nozzle supporting ball 7, moves the nozzles to the desired location and to the angle most favorable to the accomplishment of the result stated. He then 60 tightens the nuts to a sufficient degree to hold the parts in position, and proceeds with the operation of the machine.

If by any chance it is necessary to disassemble the nozzle on account of clogging 65 or the necessity for a new tip, the wear of

the tips being very rapid, the nozzle is grasped in the hand, a finger resting on the lever 15 serving to throw the latter to a position substantially at right angles to the position in which it is shown, whereby the nozzle 70 is released and removed from the ball. The tip 12 may then be removed by unscrewing the cap 35. This tip may be replaced by a new tip, and in case the nozzle is plugged by an accumulation of abrasive therein or 75 otherwise, it may obviously be easily cleared in this way.

I have thus described specifically and in detail a single embodiment of my invention in order that the nature and operation of 80 the same may be clearly understood; however, the specific terms herein are used descriptively rather than in a limiting sense, the scope of the invention being defined in the claims.

What I claim and desire to secure by Letters Patent is:

1. In an abrading machine having a rotary barrel with an opening in the axial end, a casing having an opening opposite the end of the barrel, a nozzle directed into the opening in the barrel and having a discharge end adjacent the opening, the size of the opening approaching closely the corresponding transverse dimension of the nozzle, a support for the nozzle closing the opening in the casing, and means for securing the support to the casing in various positions of adjustment in a plane transverse to the axis of rotation of the barrel providing for change of location of the nozzle, and means for securing the nozzle to the support in various angular positions providing for adjustment of the nozzle as to direction.

2. In an abrading machine, a rotary barrel having an end opening, a casing having an opening opposite the end of the barrel, a nozzle directed into the barrel opening, the periphery of the barrel opening at all points being in close proximity to the nozzle, a nozzle supporting plate closing the opening in the casing, and means for securing the plate in various positions of adjustment in a plane transverse to the axis about which the barrel rotates providing for a change of location of the nozzle, the supporting plate having an opening, a ball in which the nozzle is mounted, and means for securing the ball in the plate opening in various positions of angular adjustment providing for the angular adjustment of the nozzle.

3. In an abrading machine, a rotary barrel having an opening at the axis of rotation, a casing having an opening opposite the barrel opening, means for supplying a stream of abrasive, a nozzle for forming the stream of abrasive into a jet, the same being directed through the barrel opening, the periphery of the opening being in close proximity to the nozzle at all points and means for supporting and adjusting the nozzle comprising a ball

with a hole to receive the nozzle, a support and means for clamping the ball on the support in various positions providing for the universal adjustment of the nozzle as to direction, said support being in the form of a plate, the ball being eccentrically mounted thereon, and means for securing the support to the casing, closing the opening therein and in various positions of angular adjustment about an axis near and in the general direction of the axis of rotation of the barrel providing for adjustment of the nozzle by changing the location of the ball thereby directioning the stream of abrasive relatively to the rotary container.

4. In an abrading machine, a casing, a rotary barrel therein having an opening in its axial end, the casing having an opening opposite the barrel opening, a nozzle and a support therefor, and means for securing said support to said casing at the edges of said opening in various positions of angular adjustment about an axis close to and in the general direction of the barrel axis, closing the opening and changing the location of the nozzle relatively to the barrel axis, a ball, and means for mounting it on said support, said mounting of the ball providing for adjustment of the same about its centre, the ball having opposed openings for the nozzle, the nozzle being directed into the opening in the casing, said support and ball providing for the universal adjustment as to the direction of the nozzle relatively to said opening in the casing.

5. In an abrading machine, a casing, a rotary barrel therein having an opening concentric with its axial end, the casing having an opening opposite the opening in the barrel, a supporting plate closing the casing opening, and means for securing said support to said casing in various positions of adjustment, a ball, and means for mounting same on said support, said mounting of the ball providing for adjustment of the same about its centre, and the adjustment of the support providing for shifting the ball from place to place, the ball having opposed openings and a nozzle for abrasive mounted in said openings, the nozzle being directed into the opening in the casing, said support and ball providing for the universal adjustment as to the direc-

tion of the nozzle, the ball having a projecting portion forming a chamber to enclose the nozzle, said chamber surrounding one of the 55 openings in said ball.

6. In an abrading machine, a rotary barrel, a casing therefor, the barrel having an opening at its axial end, the casing having a larger opening opposite the opening in the 60 barrel, but eccentrically placed in relation thereto, a circular support for a nozzle covering said opening in the casing, and means for securing said nozzle support in various positions of angular adjustment about an axis 65 near and extending in the general direction of the barrel axis, a socket eccentrically placed in said support, a ball in said socket, a ring encircling the ball, and means for drawing the ring toward the socket to hold 70 the ball in adjusted position, the ball having opposed openings and a nozzle removably secured in said openings in said ball.

7. In an abrading machine, a ball, means for clamping the ball in various positions of angular adjustment, a jet directioning member carried by the ball, a rotating barrel having a hole in its axial end but slightly larger than the directioning member and near the barrel axis into which hole said member is pointed, a support for the ball to which the ball is thus clamped and on which it is eccentrically located, means for securing the support in various positions of angular adjustment in a plane transverse to the barrel 85 axis, the casing having an opening through which the nozzle is directed, the opening being closed around the ball.

8. In an abrading machine, a rotary barrel having an opening in one end, a nozzle 90 having its mouth directed into said opening, a nozzle support spaced from the end of said barrel, said nozzle being eccentrically mounted for universal movement in said support, and said support being rotatably adjustable 95 about an axis near the said barrel opening and in the general direction of the axis about which the barrel rotates for shifting the axis of said nozzle in the path of the generatrix of a cone having its apex near said opening. 100

Signed by me at Hagerstown, Maryland, this 2 day of January, 1926.
